UNITED STATES PATENT OFFICE.

JOHN P. CLULEY, OF CHICAGO, ILLINOIS.

MICROMETER CALIFER.

1,414,550.

Specification of Letters Patent. Patented May 2, 1922.

Application filed June 21, 1921. Serial No. 479,310.

To all whom it may concern:

Be it known that I, JOHN P. CLULEY, a citizen of the United States, residing at Chicago, in the county of Cook and State 5 of Illinois, have invented certain new and useful Improvements in Micrometer Calipers, of which the following is a specification.

This invention relates to micrometer calipers adapted particularly for use in stock 10 and tool rooms, paper mills and all such other places where the article to be calipered can be brought to the caliper.

It contemplates a micrometer caliper that 15 can not be easily stolen, one than can not be lost in the tailings on the floor and one that can be quickly adjusted and easily read.

With the above and other objects in view, 20 this invention consists in the construction, combination, and arrangement of parts, all as hereinafter more fully described, claimed, and illustrated in the accompanying drawings, wherein—

25 Figure 1 is a sectional view of the operable parts of the micrometer; Figure 2 is a top plan, and Fig. 3 is a sketch of the operable portion of the carrying-mechanism of the dial numerals.

30 Referring more particularly to the drawings, 1 is a cast iron base containing all of the parts of the micrometer. Through a hole 2 in said base 1, is placed a threaded bushing 3 which has in its lower portion an opening 4, admitting the plunger 5 to move freely therein and yet snugly; in its upper end it has a tapped opening 6 tapped with 1-4 35 20 left hand tap and in which the screw 7 moves.

40 The plunger 5 is provided with a hole in its center, tapped with 1-4 20 right hand tap in which the screw 8 moves; it is also provided with a slot 9 which permits the plunger 5 to move up and down in the 45 opening in the bushing 3, but not turn, as a pin 10 passes through the bushing 3 into the slot in the plunger 5.

The screws 7 and 8 are threaded on one 50 piece, screw 7 being a left hand thread and screw 8 being a right hand thread. At the end of screw 7 is provided a pin 11 fitted in at right angles to the screw. This pin travels up and down in a slot 12 provided in the bushing 13 as the screws are operated, while bushing 13 remains in its same vertical position, partaking only of a ro-

tating motion. The bushing 13 is held in its vertical position by being firmly attached to the shaft 14 and further by collars 15 and 16 which are pinned to the 60 shaft and located on either side of the dial plate 17, which in turn is screwed to the cast iron base 1 through bushings provided as in 18.

Collar 15 is also attached to a disc 19 65 Figs. 1 and 3, said disc containing two notched places for the reception of pins on another disc 20. This disc 19 is attached firmly to the collar 15 which is attached to the shaft 14. It also has two 70 pins 21 permitting a looseness of motion of cam 22 which is mounted loosely on the disc 19.

The disc 20 is provided with pins for tripping purposes as shown at 23, so that 75 as the thumb screw 24 is turned to the right and its indicator hand 30 passes 100 thousand, on the dial 17 the cam 22 will engage a pin 25 on disc 20 and start its movement to the right and pin 26 will then engage in opening 27 and continue its function until the next higher numeral has been turned up in the indicator dial. It will be noted that the looseness of the cam 22 is 80 for the purpose of making the tripping action begin at the same position whether the thumb screw is moved to the right or the left.

The disc 20 is fastened to the lower end 90 of a rotatable collar 28 suitably mounted on the base and carrying the numeral plate 29 at its upper end below the dial plate 17, so that as the disk is tripped the plate 29 turns step by step with each revolution of the thumb screw and its numerals 95 which run from 0 to 9 are successively brought into register with the opening 37 in the dial plate 17 to be read through the glass cover 31. The collar 16 which is pinned to the shaft 14 carries the main 100 indicator hand 30 above the dial 17, and the shaft 14 passes upwardly through an opening in the glass cover 31 and terminates in the thumb screw 24 which forms the operating hand-piece. The thumb screw 24 105 is connected frictionally to the shaft 14; it has a depending hollow cylindrical body having an inwardly extending annular flange at its lower end which fits snugly against a shoulder 32 thereon, the flange 110 of the thumb screw being held in frictional

engagement with the shoulder by a spiral spring 33 located in its hollow portion surrounding the upper end of the shaft and held in operative position by a screw ferrule 34 which screws onto the upper end of the shaft and seats in the upper portion of the thumb screw. The tension of the spring provides sufficient friction between the thumb screw and the shaft to 10 turn the screws of the shaft in either direction until they have moved to their stopping point, when any further turning of the thumb screw will merely overcome its frictional engagement with the shaft and not 15 effect the threads of its screws.

It is plain that when the thumb screw 24 is rotated to the left the screw 7 descends in the bushing 3 and the screw 8 withdraws from the plunger 5 forcing the foot 35 on 20 the plunger downward the distance of the movement of the screw 7 in the bushing 3 plus the distance of the movement of the screw 8 in the plunger 5, and as these threads are 20 to the inch the combined movement 25 is equivalent to ten threads to the inch, thereby doubling the movement of the foot 35 and giving a reading of 100 thousands on the dial 17 for each revolution of the pointer 30, which corresponds to the distance traveled by the foot 35 at each revolution of the screws 7 and 8. It is equally 30 obvious that when the thumb screw is rotated to the right the foot 35 is correspondingly raised. The tripping wheels trip 35 both left and right to turn the numeral plate 29; when the thumb screw is turned to the right the tripping is done at the end of each turn and in advancing order from 0 to 9 on the plate 29, and when it 40 is turned to the left the tripping is done at the beginning of each turn and in reverse order from 9 to 0 on the plate 29; with each revolution of the pointer 30 the plate turns one number so that its numerals are 45 successively brought under the opening 37 in the dial 17.

When the machine is adjusted or set the feet 35 and 36 are in contact, and the indicator hand 30 is at zero on the dial 17 and 50 the numeral plate 29 shows 0 at the aperture 37. The drawings as shown indicate the micrometer with its feet in open or extended position, which in practice represents a distance of one (1) inch; this separation between the feet is obtained by 55 turning the thumb screw 24 to the right ten (10) times, the tripping indicator being turned forward ten (10) times during this operation so that the numeral plate 29 shows 0 at the aperture when the indicator hand 30 stops at zero on the dial 17, and 60 the feet permit the insertion between them of any piece of material not exceeding one inch in thickness. After placing the material to be measured between the feet the 65

thumb screw is rotated to the left until the feet hold the piece snugly between them, extra pressure being prevented by the frictional movement of the thumb screw on the shaft 14. Assuming for example that the 70 piece of material to be measured is 750 thousands or $\frac{3}{4}$ of an inch thick, when it rests on the lower foot 36 there will be an open space or gap between the material and the foot 35 equal to the difference between 750 thousands and one thousand thousands, or 250 thousands of an inch, that the foot 35 will have no travel or cross to reach the material, and as each hundred thousands of an inch is represented by one 80 turn of the thumb-screw it will require two and one half turns of the thumb-screw to bring the foot 35 tightly against the measured piece; this operation will also turn the tripping indicator three points backward 85 and show the numeral 7 at the aperture 37. In other words as the foot 35 was extended one inch and in being returned toward its original closed position has been permitted to move only to within 750 thousands of 90 its original position owing to the material intervening, the cam 22 would move a pin 25 immediately upon starting and continue to move two other pins 25 turning the disc 20 and numeral plate 29 from 0 to 7 95 so that the latter number would appear in the aperture 37 and the indicator hand 0 would register 50, making a reading of 750 thousands of an inch. Obviously the foot 35 need not be raised to its highest position for each test; thus for example if the material is $\frac{3}{8}$ of an inch thick the thumb screw could be turned to the right four times and would trip the numeral wheel 29 four times, so that the machine would 100 read 415 thousands, and after the material is inserted the thumb screw would be turned to the left to pass its 0 position and as it does so the wheel 29 would be tripped or moved to expose the numeral 110 3 at the aperture and the hand 30 would continue until it reached 75 on its dial; the reading is then 375 thousands or $\frac{3}{8}$ of an inch.

I claim:

1. In a micrometer caliper, a base having a bushing, a plunger held against rotation in the lower end of the bushing, the bushing and plunger being oppositely threaded at their upper ends, a screw-bolt having oppositely directed screws to engage the threads of the bushing and plunger, a shaft having a thumb-piece, connections between the shaft and screw-bolt to rotate the latter, and indicating mechanism operated by the shaft. 120

2. In a micrometer caliper, a base having a bushing threaded at its upper end, a plunger held against rotation in the lower end of the bushing and having an internal 130

thread, a screw-bolt having a left hand screw engaging the thread of the bushing and a right hand screw engaging the thread of the plunger, a shaft having a thumb-
5 piece, connections between the shaft and screw-bolt to rotate the latter, and an indicating mechanism operated by the shaft.

3. In a micrometer caliper, a base having a bushing, a plunger held against rotation in the lower end of the bushing, the bushing and plunger being oppositely threaded at 10 their upper ends; a screw-bolt having oppositely directed screws to engage the bushing and plunger; a shaft having a thumb-

piece, connections between the shaft and 15 screw-bolt to rotate the latter, an indicating dial, and indicating mechanism operated by the shaft comprising a pointer on the dial, a disk on the shaft having a pair of peripheral notches, a second disk carrying a series of pins to enter the notches and a series of trip pins, a trip collar on the first disk engaging a trip pin at each revolution of the shaft, and a numeral plate 20 carried by the second disk.

25 In testimony whereof I affix my signature.

JOHN P. CLULEY.
